UNITED STATES PATENT OFFICE

HERMAN SCHORER, OF OAKLAND, CALIFORNIA

DAM

Application filed December 27, 1926. Serial No. 157,370.

This invention relates to dams.

In the drawings, Figure 1 is a sectional view of a dam;

Figure 2 shows a curve representing the curve of the columns shown in Figure 1;

Figure 3 shows the curve known as the catenary of uniform strength;

Figure 4 is a fragmentary elevational view of Figure 1 partly in section, looking in the direction of the arrow 4 of Figure 1;

Figure 5 is a fragmentary elevational view of Figure 1 looking in the direction of the arrow 5;

Figure 6 shows a column of the dam and a diagram of the forces acting thereon when the column is free from water pressure; and

Figure 7 is a diagrammatic cross section through a plurality of the hexagonal columns of Figure 1.

Referring to the drawings for a more detailed description thereof, the numeral 10 indicates the ground on which the dam 11 is built, while the numeral 12 indicates the body of water held by the dam, as shown in Figure 1.

The dam 11 comprises a plurality of hollow arched or curved columns 15 which may be made of any suitable material, such as concrete, for example, and these columns are curved in upstream direction.

The columns may be made integral with each other if desired, as shown at 16 in Figure 4 or they may be constructed as units adjacent each other. At its upper end the dam 35 terminates in a crest 21 comprising a series of semi-cylindrical members 22 spaced by flat sections 23, the latter sections having webs 24 extending rearwardly therefrom and the webs merging into the rear faces of registering tubes as shown at 25.

The columns may be of any suitable cross section but are shown in the drawings as being hexagonal.

The hollow columns are closed at their upper ends by shells 18 of any suitable form, being shown in the drawings as ellipsoidal shells. It will be seen from Figure 1 that the upstream face of the dam or that formed by the shells is inclined to the horizontal; this feature, provides against the sliding of the

dam on the foundation with the minimum amount of material in the dam and the mentioned angle is preferably between 40° and 60°.

The water pressure acting on the face of a column of my construction may be divided into a horizontal component H , and a vertical component V , as shown in Figure 2, the horizontal component H is constant from the top to the bottom of the arched column, while the vertical component at any point along the curve shown in Figure 2 consists of the component V_1 plus the weight V_c of the column above the given point. The sum of the component V_1 and V_c may be designated as V_2 . The component V_2 , it will be readily appreciated, is largest at the ground. The center line of the column is curved so that the resultant force R is always tangent to the curve. By making the thickness of the column walls so that the unit stress therein is uniform throughout, the shape of the center line is a catenary of uniform strength, which is illustrated in Figure 3, the equation of which is:

$$e^{-\frac{y}{c}} = \cos \frac{x}{c} \text{ or also } e^{\frac{y}{c}} = \frac{1}{\cos \frac{x}{c}}$$

This curve is well known and is described in "Higher Mathematics" by Merriman and Woodward, page 147.

(1) The term $e = 2.7183$ is the base of the natural logarithms.

(2) The term y is the ordinate of the curve of the catenary of uniform strength as shown in Fig. 3.

(3) The term x is the abscissæ of the curve of the catenary of uniform strength as shown in Fig. 3.

(4) c is defined as the ratio of the unit stress of the catenary of uniform strength to the unit weight of the same catenary.

By selecting a unit stress for the concrete and by determining its unit weight, the shape of the curve is fixed as is also the thickness of the walls at any given point for a given water pressure on top of the column.

When the water pressure is not acting on

the columns there is only the weight of the structure to be transmitted to the ground. The stresses for this condition are illustrated in Figure 6. In each column the weight C acting vertically downward can be divided into two components, one acting along the column axis labeled A, and the other at right angles to A and labeled B.

It will be seen from the foregoing that when the dam is subjected to water pressure the load is transmitted by direct compression parallel to the center line of the columns, so that the columns have maximum strength under the most desirable condition.

If desired, steel reinforcements may be provided in the column walls to take care of small bending stresses where necessary.

I claim:

1. A dam comprising a plurality of adjacent hollow curved columns closed at their upper ends and inclined in upstream direction, each column having walls increasing in thickness from its top to its bottom.

2. A dam comprising a plurality of curved columns closed at their upper ends and inclined in upstream direction, and each column having an axis substantially of the form of the catenary of uniform strength.

3. A dam comprising a plurality of curved hollow overlying columns closed at their upper ends, the columns curving in upstream direction, said columns being disposed at an angle to the horizontal and having walls which increase in thickness from their tops to their bottoms.

4. A dam comprising a plurality of curved overlying columns closed at their upper ends, the columns curving in upstream direction, said columns being disposed at an angle to the horizontal and having walls which increase in thickness from their tops to their bottoms and the walls of the respective columns increasing in thickness progressively from the top to the bottom column.

5. A dam for holding water or the like comprising a plurality of columns curved along the lines of principal compressive stress and inclined toward the water and interconnected to have their ends present a water-tight face to the water.

6. A dam for holding water or the like comprising a plurality of hollow columns curved along the lines of principal compressive stress and inclined toward the water and closed and interconnected at the upper ends to have the latter present a water-tight face.

7. A dam comprising a plurality of overlying curved columns closed at their upper ends disposed at an angle to the ground inclined in upstream direction, each column increasing in thickness from its top to its bottom, and the respective columns increasing in thickness progressively from the top to the

bottom column, the thickness of said columns at any point being such that the compressive stress is uniform throughout the columns when the full water pressure is acting on the face of the dam.
